US00D819066S

(12) **United States Design Patent** (10) Patent No.: **US D819,066 S**
(45) Date of Patent: **** May 29, 2018**

(54) **DISPLAY PANEL WITH A GRAPHICAL USER INTERFACE**

(71) Applicant: **C T CORPORATION SYSTEM**, New York, NY (US)

(72) Inventors: **Stephen C. Anderson**, Morris Plains, NJ (US); **Kimberly D. Friedman**, Brooklyn, NY (US)

(73) Assignee: **Corsearch, Inc.**, New York, NY (US)

(**) Term: **15 Years**

(21) Appl. No.: **29/563,531**

(22) Filed: **May 5, 2016**

(51) **LOC (11) Cl.** **14-04**

(52) **U.S. Cl.**

USPC **D14/486**

(58) **Field of Classification Search**

(57) **CLAIM**

The ornamental design for a display panel with a graphical user interface, as shown and described.

DESCRIPTION

The FIGURE is a front view of a display panel with a graphical user interface showing our new design.

The outermost rectangle illustrates the display panel. The broken lines showing of portions of the display panel with a graphical user interface illustrate portions of the display panel with the graphical user interface which form no part of the claimed design.

1 Claim, 1 Drawing Sheet
